UNITED STATES PATENT OFFICE

2,152,567

CHASER FOR DIE HEADS

Charles A. Reimschissel, Waynesboro, Pa., assignor to Landis Machine Company, Waynesboro, Pa., a corporation of Pennsylvania

Application July 3, 1937, Serial No. 151,913

5 Claims. (Cl. 10—104)

This invention relates to thread cutting chasers and holders and particularly to chasers of the tangential type.

Chasers of this kind are, as is well known in the art, held in suitable holder blocks by means of clamps drawn into firm engagement with clamping surfaces provided on the chasers. An example of this kind of chaser mounting is had in United States Patent No. 1,906,176, granted 10 to S. F. Newman et al. on April 25, 1933. As will be readily understood, a considerable force must be exerted on the chaser by the clamps to the end that the chaser is held firmly against the co-operating seating surface on the chaser 15 holder to prevent relative movement between these two elements. Also, in order to insure accuracy and uniformity of performance of the chasers, the clamping action should be such that the chasers are at all times held in the same 20 relative position in the holder, that is, the back or seating surface of the chaser should always be held against the seating surface of the holder with uniform pressure throughout the entire areas of the surfaces.

25 In prior devices of this kind, it has been found that the clamping force is so applied as to cause a slight "tilting" or "rocking" of the chaser with respect to the seating surfaces, which not only results in inaccuracies in the cutting action, but, 30 furthermore, tends to greatly reduce the force of friction between chaser and holder thereby making it possible for the chaser to move slightly with respect to the holder under the reaction forces set up during the cutting operation.

35 It is, therefore, a major object of this invention to provide an improved thread chaser and holding means so designed that the resultant of the force exerted by the holding or clamping means is directed centrally of the seating 40 surfaces and perpendicular thereto, whereby the tendency of the clamping force to tilt the chaser is obviated.

Another important object of my invention is to provide a chaser or thread cutting tool with 45 clamping and base seating surfaces so arranged with respect to each other and to a back seating surface that the clamping force is reflected by the first two surfaces as a resultant acting centrally of and perpendicular to the back seating surface of the chaser and also centrally of and normal to the seating surface of the holder.

50 A still further object of my invention is to provide a novel and improved chaser holder and clamp in which the clamp seating surface of the holder and the clamping surface of the clamp

are each inclined equally from a line parallel to the clamp securing means whereby the force applied to the chaser is directed parallel to the back seating surface of the chaser and thus intersects the clamping surface of the chaser and the base seating surface of the chaser at the same angle.

In devices of this character, the force applied by the clamping means is of considerable magnitude, as has been previously noted, and, furthermore, the chasers are made of high speed steel which sometimes leads to failure of the chaser by cracks starting at the acute angle of the dovetail usually provided adjacent to the chaser clamping surface. It is, therefore, a still 15 further object of my invention to provide an improved thread chaser which is formed so as to eliminate this sharp angle between the clamping surface and the body of the chaser thereby preventing the formation of incipient cracks and 20 greatly enhancing the strength and life of the chaser.

Also, in chasers of this type, wherein the clamp seats against an inclined clamping surface, another place of weakness is present at 25 the juncture of the clamping surface and the back seating surface of the chaser. Due to the relative brittleness of the material used for the chasers and the intensity of the clamping force, the thin and sharp edges formed by the aforementioned surfaces is very often "chipped" or broken under the clamping action. Thus, a still further object of my invention is to provide an improved chaser in which a comparatively thick 30 edge is located at the juncture of the clamping 35 surface and back seating surface, which thickened edge is sufficiently strong to withstand the clamping forces.

The above, and further objects, will become apparent from a study of the following detailed 40 description of a preferred embodiment of my invention together with the appended claims when considered in conjunction with the accompanying drawing, in which:

Figure 1 is a face view of a die head provided 45 with a set of chasers in their holders and embodying my invention.

Figure 2 is a partial section through a chaser and its holder taken on the line 2—2 of Figure 1, 50 and on an enlarged scale.

Figure 3 is a view similar to that of Figure 2, taken on the line 3—3 of Figure 1.

Figure 4 is a face view of the improved chaser 55 of my invention; and

Figure 5 is an end view of a slightly modified form of chaser.

Referring now to the drawing, in which like reference characters are used to designate the same elements wherever they appear in the several views, and with particular reference to Figure 1, the reference character 2 designates a conventional die head carrying holders 4. Chasers 6 are mounted in the holders by means of clamps 8 held in place by screws 10.

Turning now to Figure 2 and 3 wherein the shape of my improved chasers, holders, and clamps are shown, chaser 6 is provided with base seating surface 12, back seating surface 16, and clamping surface 14. Small beveled surfaces 18 and 20 connect these three surfaces as will be evident upon inspection of these views. The surface 14 forms a dovetail and is connected by undercut surface 22 to a seating surface 24, the latter being parallel to, but offset from, surface 16. Surfaces 14 and 22 are formed by a curved surface or fillet 26, the purpose of which will be explained later. Chaser 6 is provided with cutting serrations 28 and a leading edge 30 in the usual manner.

Surface 16 bears against a co-operating flat surface 32 on holder 4, and base surface 12 bears against a co-operating surface 34. Surface 24 rests against a surface 36 to give support to the leading edge of the chaser. The holder is also provided with a surface 38 on which rests an end surface 40 of clamp 8. The opposite end of the clamp carries an inclined surface 42 engaging surface 14 of chaser 6.

The angular relationship of the several surfaces is illustrated by the broken lines R, x, y, and z and angles a—a in Figure 3. Surfaces 38 and 34, and co-operating surfaces 40 and 12 are parallel (see lines x and y). Surfaces 12 and 14 are each inclined equally with respect to surface 16 (see lines y and z and angles a—a). Since the axis of screw 10 is parallel to surface 32, it follows, by simple geometry, that surfaces 14, 42 and 38, 40 are equally inclined with respect to the line of action of the force exerted in holder 8 by the screw 10.

Upon tightening of screw 10, the clamp is pressed at one end against surface 38 while the other end bears on the inclined surface 14 of the chaser; and, as will readily be understood, the chaser is firmly held in place in the holder by screw 10 with surfaces 10 and 32 and surfaces 24 and 36 pressed together, and with surfaces 12 and 34 also engaged.

It will be observed that, due to the equal inclination of surfaces 38, 40 and 14, 42 with respect to the direction of the force exerted by the screw 10, the resultant force acting on chaser surface 14 will be directed in parallelism with the surfaces 16 and 32. Furthermore, as surfaces 12 and 14 are equally inclined with respect to the surface 16, the resulting clamping force reacts equally against each side of the chaser 6, on the surfaces 14 and 12, and the back seating surface 16 is forced against the surface 32 of holder 10 with a uniform pressure throughout. In other words, the resultant of the clamping force acts normal to and centrally of surfaces 16 and 32 (see line R, Figure 3).

As a consequence of this arrangement of the several mutually engaging surfaces, there is no tendency for the clamping force to "tilt" or "cock" the chaser in the holder, and a maximum frictional grip is provided. In this manner the chaser is held in place on the holder with the

utmost security, and upon adjustment therewith, as is necessary after grinding, is always returned to the same relative position with respect to the holder, as far as the location of the cutting serrations is concerned, thus insuring 5 accuracy and uniformity of performance of the chaser.

It will also be observed that the chaser has a relatively thickened edge adjacent to the bevel 18 to resist the stress resulting from the pressure 10 of clamp 8. With this arrangement an unusually strong supporting surface is provided, and danger of damaging the chaser by "chipping" or "breaking" at this point is greatly reduced and, in fact, practically eliminated.

Also, the provision of the fillet 26 adds considerably to the ability of the chaser to stand up under the clamping strains. This is due to the fact that incipient cracks resulting from hardening strains generally present at this point when 20 the surfaces 14 and 22 are joined by an acute and sharp angle, as is the usual practice, are obviated. Thus, the tendency of the chaser to break at this point is practically eliminated.

The bevel 20 also serves a very useful purpose 25 by preventing "chipping" and "breaking", and further provides a clearance space into which fine chips or cuttings may collect, thus permitting proper seating of the surfaces 12 and 34. Furthermore, with this construction, slight wear 30 in the cutter used to machine the surfaces 32 and 34 on the holder will not cause trouble in the later fitting of the chasers.

The clearance surface 22, which may take the slightly modified form 22a shown in Figure 5, 35 in which corresponding portions of the chaser are designated by reference characters similar to those of Figures 2 and 3 with the addition of the letter "a", makes it possible to machine the two surfaces 14 and 24, and 14a and 24a, with a 40 combination cutter. This greatly facilitates the production of chasers and results in a considerable savings.

From the foregoing it will be evident that I have provided a novel and improved chaser and 45 chaser holding means wherein the chaser is greatly increased in strength and durability and is held in place in the holder in a very positive and accurate manner.

The invention may be embodied in other specific 50 forms without departing from the spirit or essential characteristics thereof. The present embodiment is, therefore, to be considered in all respects as illustrative and not restrictive; the scope of the invention being indicated by the appended claims 55 rather than by the foregoing description; and all changes which come within the meaning and range of equivalency of the claims are, therefore, intended to be embraced therein.

What is claimed and desired to be secured by 60 United States Letters Patent is:

1. A chaser holder having a surface adapted to co-operate with the back seating surface of a chaser, a second seating surface inclined with respect to said first named holder surface, and a 65 clamp seating surface offset from and parallel to said second seating surface, said holder being provided with a threaded clamping screw bore having its axis arranged parallel to said first-named surface.

2. In combination a chaser, a chaser holder and a chaser clamp means, said holder being provided with offset and parallel surfaces and having a seating surface; a chaser having a seating surface engaging said holder seating surface and a sec- 75

- ond surface engaging one of said offset surfaces, a clamping surface on said chaser, said second surface and said clamping surface being equally inclined with respect to said seating surface; said 5 clamp means having seating surfaces engaging said chaser clamping surface and the other of said offset surfaces; means to apply a force to said clamp means; said clamp seating surfaces and the surfaces on said chaser and holder co-operating 10 therewith being inclined equally with respect to the line of action of said force whereby the resultant of said force is directed normal to and centrally of said holder and chaser seating surfaces.
3. A chaser comprising a body portion having a 15 back seating surface; a second seating surface on said body, said last named seating surface being offset from and parallel to said back seating surface; a clamping surface inclined with respect to said seating surfaces and joined at one edge to said back seating surface by means of a beveled portion; an undercut surface joining the other edge of said clamping surface to said offset surface; said undercut surface extending a substantial distance beyond said first named edge of said 20 clamp surface, and a base seating surface inclined toward said clamping surface, said base seating surface and said clamping surface making equal angles with said back seating surface. 25
4. A chaser comprising a body having cutting 30 serrations thereon and provided with a clamping
- surface, a base seating surface, a first back seating surface and a second back seating surface offset from and parallel to said first back seating surface, said seating surfaces being adapted to seat against corresponding holder surfaces, and 5 said clamping surface being adapted to cooperate with a corresponding clamp surface; said clamping surface and said base seating surface being inclined equally with respect to said back seating surfaces and toward each other, so that the 10 resultant of a clamping force applied to said clamping surface in a direction parallel to said back seating surfaces acts centrally of and perpendicular to said back seating surfaces.
5. In a chaser holding device, a chaser holder, a 15 clamp means and means to apply a force to said clamp means, two parallel and offset chaser back seating surfaces on said holder, a chaser base seating surface and a clamp engaging surface on said holder, said last-named two surfaces being 20 inclined with respect to said back seating surfaces and parallel to each other, a chaser contacting surface and a holder engaging surface on said clamp means, and means for applying a clamping force to said clamp in a direction parallel to 25 said offset chaser back seating surfaces, said clamp surfaces being inclined equally with respect to the line of action of the force applied to said clamp.

CHARLES A. REIMSCHISSEL. 30
